TELEPHONE SYSTEM

Harry G. Evers, Chicago, Ill., assignor to Associated Electric Laboratories, Inc., Chicago, Ill., a corporation of Delaware

Application April 28, 1939, Serial No. 270,540

7 Claims. (Cl. 179—6.3)

The present invention relates to telephone systems and, more particularly, to improvements in paystation line adapter circuits of the general character disclosed in Patent No. 1,376,814—
5 Jacobsen, granted May 3, 1921.

In automatic telephone systems wherein a portion of the lines in service extend to substations of the paystation type, provisions are universally made for preventing desired connections, resulting from calls originating at the paystations, from being established until the correct coin deposits have been made at the calling stations. Several different types of circuits have been devised for this purpose. In the arrangement of
10 the above-mentioned Jacobsen patent, the circuits are so arranged that a desired connection originating at a paystation may be routed to a desired called substation in response to operation of the calling device provided at the calling paystation, without the deposit of a coin in the coin-receiving means provided at the calling station. When, however, the call is answered at the called substation, the connection is broken to prevent communication thereover and is not recompleted
15 until the calling party makes the appropriate coin deposit. This mode of operation is achieved through the provision of paystation adapter circuits, one of which is interposed in the incoming trunk line of each of the first numerical switches, i. e., the first selector switches to which the paystation lines have access. More particularly, each of these circuits is provided with an electro-polarized relay which is operative only in response to the reversal of battery over an established calling loop circuit routed by way of the circuit. This polarized relay is arranged to open a point in the associated trunk line, thus interrupting the connection routed by way of the trunk line and to hold the connection open until
20 a coin is deposited in the coin-receiving means of the call originating paystation.

It is an object of the present invention to provide an improved paystation line control circuit of the general character just described which is arranged for use in conjunction with the individual paystation lines of a telephone system.

It is a further and more specific object of the invention to provide an improved paystation control circuit of the character indicated wherein
25 a unidirectional conductive device is utilized in conjunction with the connection interrupting relay for the purpose of poling this relay to respond only to current of a predetermined polarity traversing the associated line.

55 The invention is illustrated in its embodiment

in an automatic telephone system which comprises a plurality of lines, one of which extends to a substation of the paystation type; together with automatic switching apparatus for establishing connections between the lines and including a group of numerical switches having access to the paystation line. The automatic switching apparatus is operative, on a call originating at the paystation, to route a connection from the paystation line to a second or called one of the lines, the connection as ultimately established comprising a first loop circuit which includes the first or calling line and a second loop circuit which includes the second or called line. In accordance with one feature of the present invention there is provided in association with the paystation line, a paystation control circuit which comprises a connection interrupting relay including an operating winding and having an operating circuit which parallels a portion of the first loop circuit. This operating circuit has included therewith a unidirectional conductive device in the form of a copper oxide rectifier which functions to prevent the connection interrupting relay from operating when the first loop circuit is initially completed. The indicated relay is controllable over the called line to prevent the established connection from being used for communicating purposes until the proper coin deposit is made at the calling paystation. Circuit means comprising a plurality of additional relays controllable from the paystation are provided for rendering the established connection operative for communicating purposes in response to the deposit of a coin in the coin-receiving means of the calling paystation. One of the last-mentioned relays functions as a line switching relay and its operation is required in routing connections both to and from the paystation terminating the associated line. The arrangement is such that on calls incoming to the paystation line, this line switching relay is caused to operate in response to seizure of the line by one of the final selector or last numerical switches having access thereto.

Further features of the invention pertain to the particular arrangement of the circuit elements whereby the above and additional operating features are obtained.

The novel features believed to be characteristic of the invention are set forth with particularity in the appended claims. The invention, both as to its organization and method of operation, together with further objects and advantages thereof will best be understood by reference to the specification taken in connection with the accom-

panying drawing, the single figure of which illustrates an automatic telephone system having embodied therein an improved paystation control circuit of the character briefly described above.

5 Referring to the drawing, the system there illustrated comprises a plurality of subscribers' lines including the lines 10 and 11 extending, respectively, to the substations A and B, together with automatic switching apparatus including a 10 pair of line switches 12 and 15, individual to the lines 10 and 11, a selector switch 13 and a connector switch 14 for setting up connections between the various lines. Preferably, each of the line switches is of the well-known rotary 15 type and the selector and connector switches are of the conventional Strowger type employing vertical and rotary motion switching mechanisms for performing the required line selecting operations. The line switches 12, 15, etc., individual 20 to the subscribers' lines, are conventionally known as non-numerical switches for the reason that they are ineffective to perform any line selecting functions other than those of selecting idle ones of the selector switches. The selector and connector switches, on the other hand, are commonly known as numerical or directly controlled switches in that they are operative to perform particular line selecting functions in response to 25 impulses transmitted thereto.

30 Any desired number of the subscribers' lines extending to the automatic switching apparatus of the system may be arranged to serve substations of the paystation type. The lines extending to these substations are individually provided 35 with paystation control circuits identical in arrangement with the circuit 16 shown in association with the line 10 extending to the paystation A. Briefly described, this paystation control circuit comprises a line relay R170, a slow-to-re- 40 lease line switching relay R150, a combined cutoff and line switching relay R160, and a bridging relay R110 which includes an operating winding arranged to be bridged across the conductors of the line 10 in series with a unidirectional con- 45 ductive device in the form of a copper oxide rectifier 133. The relay R110 is arranged to control a line switching relay R100 to interrupt an established connection routed from the sub- 50 station A over the line 10 to a desired called substation when the call is answered at the 55 called substation. For the purpose of recompleting the connection, in order that communication may be held thereover, there are provided three control relays R120, R130 and R140, the second of which is of the marginal type and is con- 60 trollable from the substation A to cause the restoration of the relays R110 and R150 and the operation of the relay R160, thereby to recom- 65 plete the established connection.

60 The apparatus provided at the substation A conventionally comprises coin-receiving means which includes a coin deposit chute, a fragment of which is indicated at 17. Coins deposited in this chute are arranged to control the operation 65 of a switching device 18 which is provided for the purpose of controlling the relay R130 embodied in the paystation control circuit 16. In addition to the switching apparatus embodied in the line terminating exchange, there is provided 70 the usual ringing current apparatus together with a paystation tone current source and an answer tone current source. Since the illustration of these elements is not essential to an understanding of the invention, they have been 75 omitted from the drawing. In order more clearly

to describe the operation of the paystation control circuit 16, a portion of the relay equipment embodied in the connector switch 14 has been illustrated in detail. More particularly, this equipment comprises a line relay R40 and a back 5 bridge or battery reversing relay R30 which is arranged to operate in the usual manner when a call routed by way of the connector switch 14 is answered at the called substation.

Referring to the operation of the apparatus and 10 considering first a call initiated at the substation A, when the calling party removes the receiver provided at this substation from its supporting hook or cradle, a loop circuit is completed over which the line relay R170 is energized. This circuit extends from ground by way of the lower winding of R170, RA164, RA158, RA103, the conductor 10b, the switch springs 19 and 20, the bridge across the conductors of the line 10 at the 15 substation A, the conductor 10a, RA101, RA152, RA161 and the upper winding of R170 to battery. When this circuit is completed, the relay R170 operates to open, at RA172, a point in the circuit traced hereinafter for energizing the relay R160, and to prepare at RA171, a circuit for 20 energizing the slow-to-release relay R150. At RA171 the relay R170 also completes a path for impressing a paystation tone voltage upon the control conductor 10c, this path extending 25 from one terminal of the tone current source by way of C146, the condenser 145, RA171 and RA162 to the conductor 10c. Completion of this path is without effect on local calls of the character under 30 consideration, this path forming a link in a circuit for transmitting to an operator's position the usual paystation identifying signal on toll calls originating at the station A. At RA173, the relay R170 completes an auxiliary loop circuit including the resistor 174 and extending to the line 35 switch 12. The line switch 12 responds to the completion of the auxiliary loop circuit by operating to select an idle one of the selector switches to which it has access. Assuming, for example, 40 that the selector switch 13 is the first available idle selector switch, when the wipers of the line switch 12 encounter the trunk line extending to this selector switch, the auxiliary loop circuit is switched through thereto. As a result, the selector switch 13 is conditioned to respond to the first series of impulses of the directory number 45 designating the substation desired by the calling party. In addition, the relay equipment of the selector switch 13 operates in the usual manner to impress ground potential upon the control conductor of the trunk line incoming thereto, this ground potential being extended through the 50 operated line switch 12 to the private conductor 10c of the line 10, thereby to mark the line 10 as busy in the bank contacts of the connector 55 switches having access thereto. When ground potential is impressed upon the conductor 10c, the slow-to-release relay R150 is energized over a circuit including this conductor, RA162, RA171 and the winding of R150. Upon operating, the relay R150 completes, at RA156, a circuit for energizing the lower winding of the relay R130 in 60 parallel with the lower winding of the relay R110, one branch of this circuit extending by way of RA141 and the lower winding of R130 to battery and the other branch extending by way of the resistor 115 and the lower winding of R110 to battery. At RA155, the relay R150 opens a further 65 point in the above-mentioned circuit for energizing the relay R160. At RA154, the relay R150 completes an obvious holding circuit for itself. 70 75

At RA153, the relay R150 completes the operating circuit for the relay R110, this operating circuit paralleling a portion of the loop circuit extending to the selector switch 13. More particularly, 5 the operating circuit for the relay R110 extends from ground through one of the windings of the line relay conventionally embodied in the selector switch 13 over one side of the established loop circuit, through the upper winding of R110 and by 10 way of RA111, the rectifier 133, RA153, the other side of the established loop circuit extending to the selector switch 13 and the other winding of the line relay embodied in this selector switch to battery. The rectifier 133 included in this circuit is so poled that current is prevented from traversing the operating winding of the relay R110 at this time.

At its armatures RA151, RA152, RA157 and RA158, the relay R150 completes a loop circuit 20 extending from the calling substation through to the selector switch 13 in an obvious manner. At RA152 and RA158 and their respective associated resting contacts, the relay R150 opens two points in the above-traced circuit for energizing the line relay R170, causing this line relay to restore. Upon restoring, the relay R170 opens, at RA173, a point in the above-described auxiliary loop circuit including the resistor 174. At RA171, the relay R170 opens a point in the operating 25 circuit for the relay R150. At RA172, the relay R170 prepares a point in the previously mentioned circuit for energizing the relay R160.

When the relay R150 operates to complete the 30 above-traced circuits for energizing the respective lower windings of the relays R110 and R130, the relay R130 operates to complete, at RA131, an obvious circuit for energizing the slow-acting relay R120. At RA132, the relay R130 opens a point in another circuit, traced hereinafter, for 35 energizing the relay R160. The relay R120, upon operating, opens, at RA121, a second point in the last-mentioned circuit. Due to the resistance of the resistor 115 the flow of current over the above-traced circuit for energizing the lower winding 40 of the relay R110 is insufficient to cause this relay to operate in response to operation of the relay R150.

Following the operation of the relay R120, the 45 switching apparatus is conditioned to respond to the impulses making up the digits of the directory number designating the desired called substation. Assuming, for example, that the substation B is the called substation and, further, that the selector switch 13 and the connector switch 14 are 50 utilized in extending the connection to the called line 11, the selector switch 13 responds to the impulses of the first digit dialed at the substation A by operating to select an idle one of the connector switches having access to the called line, 55 which connector switch, in the present case, is assumed to be the switch 14. When this connector switch is selected by the switch 13, the calling loop circuit is extended thereto so that the line relay R40 is energized thereover. This line 60 relay responds to the impulses of the second and third digits by causing the Strowger switching mechanism embodied in the connector switch 14 to operate to the position corresponding to the called line 11. At the end of the third and final 65 digit, the called line is tested in the usual manner to determine the idle or busy condition thereof and if found busy the usual busy tone signal is returned to the calling party. If, on the other hand, the line 11 is idle at the time it is selected, 70 75 the control apparatus of the connector switch 14

functions to impress ground potential upon the control conductor of this line for the purpose of marking the line as busy and to project ringing current over the line in order to energize the signal device provided at the called substation B. 5

When the call is answered at the called substation, a second loop circuit, including the called line 11, is completed between the substation B and the connector switch 14. The back bridge relay R30 is energized over this second loop circuit and 10 operates its armatures RA31 to RA34, inclusive, to reverse the direction of current flow over the calling loop circuit in the usual manner. When the direction of current flow over the calling loop circuit is reversed, the rectifier 133 no longer 15 blocks the passage of current through the upper winding of the relay R110 with the result that this winding is energized and the relay R110 operates. Upon operating, the relay R110 first completes at the "X" contacts associated with 20 RA112 an obvious path for short-circuiting the resistor 115. Following the completion of this short-circuiting path, the current flow through the lower winding of the relay R110 is sufficient to maintain this relay operated independently of 25 its upper winding. At RA111, the relay R110 opens a point in its operating circuit, thus clearing the established connection of the shunt impedance represented by the upper winding of the relay R110. At RA114, the relay R110 prepares a 30 circuit, traced hereinafter, for impressing across the conductors of the line 10 the voltage of the answer tone source, not shown. At RA113, the relay R110 completes a circuit for energizing the relay R100, this circuit extending from ground at 35 RA156 by way of RA113 and the winding of R100 to battery. Upon operating, the relay R100 completes, at RA102, an obvious holding circuit for itself. At RA101 and RA103, the relay R100 opens two points in the established connection 40 extending between the calling and called substations A and B respectively, and completes the above-mentioned circuit for conducting answer tone current through the receiver provided at the calling substation A. More particularly, the 45 path traversed by this current may be traced as extending from one terminal source of the answer tone current by way of C105, the condenser 104, RA114, RA103, the conductor 10b, the springs 19 and 20, the receiver at the calling substation, 50 the conductor 10a, RA101, the resistor 107 and the exchange battery to the opposite terminal of the answer tone current source. Reproduction of this current by the receiver provided at the calling substation serves to signal the calling 55 party that the desired connection has been obtained. At RA101 and RA103, the relay R100 also completes a circuit for energizing the upper winding of the relay R130 in series with the winding of the relay R140. This circuit extends from 60 ground by way of the adjustable resistor 144, the winding of R140, the upper winding of R130, RA103, the conductor 10, the switch springs 19 and 20, the bridge across the line conductors at the substation A, the conductor 10a, RA101 and 65 the resistor 107 to battery. When energized over this circuit, the relay R140 operates to open, at RA141, the operating circuit for the relay R130. Due to the energized condition of the upper winding of R130, this relay remains in its operated 70 position. At RA142, the relay R140 prepares the previously mentioned second circuit for energizing the line switching relay R160. At RA143 the relay R140 recompletes the previously described auxiliary loop circuit, which circuit now 75

- extends through the switches 12 and 13 to the operated connector switch 14. The purpose of re-completing this auxiliary loop circuit is to maintain the switches 12, 13 and 14 operated, it 5 being pointed out that the calling loop circuit is now interrupted at the armatures RA101 and RA103 of the operated relay R100. It is pointed out that by making the resistor 144 adjustable, the resistance of the circuit serially including the 10 winding of R140 and the upper winding of R130 may be adjusted for positive response of the marginal relay R130 regardless of the resistance of the line 10 or of another line with which the control circuit 16 may be associated.
- 15 The calling party, upon hearing the answer tone signal, is required to deposit a coin in the coin deposit chute 17 of the coin-receiving means in order to cause the connection to be recompleted. Passage of this coin through the chute 20 20 25 30 35 40 45 50 55 60 65 70 75
- 17 serves to actuate the switching device 18 so that the springs 19 and 21 are closed and the springs 19 and 20 are opened. As a result, the resistor 22 is serially included in the above-traced circuit for energizing the upper winding of the relay R130 in series with the winding of the relay R140. Inclusion of the resistor 22 in this circuit serves to decrease the current flow thereover to a point such that the relay R130 is insufficiently energized to remain operated. Accordingly, the relay R130 restores to open, at RA131, the operating circuit for the relay R120 and to prepare, at RA132, a further point in the circuit for energizing the relay R160. Thereafter, and when the relay R120 restores, the last-mentioned 30 35 40 45 50 55 60 65 70 75 circuit is completed, this circuit extending from ground by way of RA156, RA121, RA132, RA142 and the lower winding of R160 to battery. When energized over this circuit, the relay R160 operates to complete, at the "X" contacts associated with RA163, an obvious holding circuit for itself, this holding circuit including the grounded conductor 10c of the line 10. At RA161 and RA164, the relay R160 opens two further points in the previously traced loop circuit for energizing the line relay R170 and prepares two points in an alternative loop circuit extending from the substation A to the connector switch 14. At RA162, the relay R160 opens the holding circuit for the slow-to-release relay R150, causing the last-mentioned relay to restore. Upon restoring, the relay R150 completes, at RA155, a multiple holding circuit for the relay R160 and prepares, at RA152 and RA158, two additional points in the above-mentioned alternative loop circuit. At RA151 and RA157, the relay R150 opens two points in the initially completed loop circuit extending from the substation A to the switches 13 and 14. At RA153, the relay R150 opens a further point in the previously traced operating circuit for the relay R110. At RA154, the relay R150 opens an additional point in its own holding circuit. Finally, at RA156, the relay R150 opens a point in the common portion of the operating and holding circuits for the relays R100, R110, R120 and R130. As a result, the relays R100 and R110 are caused to restore, the first-mentioned thereof functioning to open, at RA101 and RA103, two points in the above-traced circuit traversed by the answer tone current and two points in the above-traced circuit for energizing the upper winding of the relay R130 in series with the winding of the relay R140. At these same armatures and their respective associated resting contacts, the relay R100 completes the above-mentioned alternative loop circuit ex-

tending from the substation A to the connector switch 14, thereby to complete the desired communicating or talking circuit between the calling and called substations. When the relay R140 restores in response to the release of the relay R100, 5 it opens, at RA143, the above-traced auxiliary loop circuit including the resistor 174, thereby to clear the established talking circuit of the impedance represented by this resistor. Following the release of the relay R140, no further operation of the apparatus occurs until the connection is cleared out.

The manner in which the connection is released depends upon the circuit arrangement of the control apparatus embodied in the connector switch 14. For example, this apparatus may be so arranged that the release of the connection is under the control of the last party to hang up. Alternatively, this apparatus may be so arranged that the release of the established connection is 20 entirely under the control of the calling party. Assuming the latter type of arrangement, when the calling party replaces the receiver provided at the substation A upon its supporting hook or cradle, the calling loop circuit is interrupted with 25 the result that the switches 14, 13 and 12 are released in the order named and in a manner well understood in the art. During the release of the connector switch 14, the control apparatus of this switch functions to remove ground potential from 30 the private conductor of the line 11 and to substitute battery potential thereon, thus identifying the line 11 as idle in the bank contacts in the connector switch having access thereto. Similarly, when the switch train is released, ground potential is removed from the private conductor 10c and battery potential is impressed upon this conductor to mark the line 10 as idle. When the conductor 10c is disconnected from ground, the relay R160 is deenergized and restores. Thus, the 40 paystation control circuit 16 is fully released and is conditioned for further use.

On a call incoming to the substation A, the line switching relay R160 is caused to operate to extend the desired connection to the called substation immediately the line 10 is seized by the final selector or connector switch through which the call is routed. For example, if a call is routed from the substation B over the line 11 and through the line switch 15, the selector switch 13 and connector switch 14 to the line 10 at a time when the last-mentioned line is idle, the control apparatus of the connector switch 14 functions to impress ground potential upon the private conductor 10c of the line 10 shortly following the selection of this line. In response to this operation, the line switching relay R160 is energized over a circuit extending by way of the grounded conductor 10c, RA172, RA155 and the upper winding of R160 to battery. 60 Upon operating, the relay R160 first completes at the "X" contacts associated with RA163, the previously traced holding circuit for itself. At RA162, the relay R160 opens a point in the previously traced operating and holding circuits for the relay R150. At RA161 and RA164, the relay R160 opens two points in the previously traced operating circuit for the relay R170 and extends a connection to the called substation A so that ringing current may be projected over the line 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 move ground potential from the control conductor 10c. On calls of the character just described, i. e., calls incoming to the substation A, the relay R160 is the only relay which is affected, the remaining relays of the control circuit 16 serving no purpose in the completion of calls of this character.

While there has been described what is at present considered to be the preferred embodiment of the invention, it will be understood that various modifications may be made therein, and it is contemplated to cover in the appended claims all such modifications as fall within the true spirit and scope of the invention.

15 What is claimed is:

1. In a telephone system, a substation, a first line extending to said substation, a second line, automatic switching means for establishing a connection between said lines on a call originating at said substation, said connection comprising a first loop circuit including said first line and a second loop circuit including said second line, a relay, an operating circuit for said relay, said operating circuit paralleling a portion of said first loop circuit, means comprising a unidirectional conductive device included in said operating circuit for preventing said relay from operating in response to completion of said first loop circuit, means operative to cause current to traverse said operating circuit in the proper direction to cause operation of said relay when said second loop circuit is completed, means responsive to operation of said relay for preventing communication over said connection, and means controllable from said substation for subsequently conditioning said connection for communication thereover.

2. In a telephone system, a substation including means for receiving coins or the like, a first line extending to said substation, a second line, automatic switching means for establishing a connection between said lines on a call originating at said substation, said connection comprising a first loop circuit including said first line and a second loop circuit including said second line, a relay, an operating circuit for said relay, said operating circuit paralleling a portion of said first loop circuit, means comprising a unidirectional conductive device included in said operating circuit for preventing said relay from operating in response to completion of said first loop circuit, means operative to cause current to traverse said operating circuit in the proper direction to cause operation of said relay when said second loop circuit is completed, means responsive to operation of said relay for preventing communication over said connection, and means operative in response to the deposit of a coin in said coin-receiving means for conditioning said connection for communication thereover.

3. In a telephone system, a pair of lines, means for establishing a connection between said lines, said connection comprising a first loop circuit including the calling one of said lines and a second loop circuit including the called one of said lines, a relay, an operating circuit for said relay, said operating circuit paralleling a portion of said first loop circuit, means comprising a unidirectional conductive device included in said operating circuit for preventing said relay from operating in response to completion of said first loop circuit, means operative to cause current to traverse said operating circuit in the proper direction to cause operation of said relay when said second loop circuit is completed, means respon-

sive to operation of said relay for opening said first loop circuit, and means controllable over said calling line for re-completing said first loop circuit.

4. In a telephone system, a substation including means for receiving coins or the like, a first line extending to said substation, a second line, means for establishing a connection between said lines on a call originating at said substation, said connection comprising a first loop circuit including said first line and a second loop circuit including said second line, a relay, an operating circuit for said relay, said operating circuit paralleling a portion of said first loop circuit, means comprising a unidirectional conductive device included in said operating circuit for preventing said relay from operating in response to completion of said first loop circuit, means operative to cause current to traverse said operating circuit in the proper direction to cause operation of said relay when said second loop circuit is completed, means responsive to operation of said relay for opening said first loop circuit, and means operative in response to the deposit of a coin in said coin-receiving means for re-completing said sec- 25

ond loop circuit.

5. In an automatic telephone system, a pair of lines, means including impulse responsive switches for establishing a connection between said lines, said connection comprising a first loop circuit including the calling one of said lines and a second loop circuit including the called one of said lines, a relay, an operating circuit for said relay paralleling a portion of said first loop circuit, means comprising a unidirectional conductive device included in said operating circuit for preventing said relay from operating in response to completion of said first loop circuit, means operative to cause current to traverse said operating circuit in the proper direction to cause operation of said relay when said second loop circuit is completed, means responsive to operation of said relay for opening said first loop circuit, and means operative in response to the deposit of a coin in said coin-receiving means for re-completing said sec- 30

ond loop circuit.

6. In an automatic telephone system, a sub- 35

station, a first line extending to said substation, a second line, automatic switching apparatus in-

cluding non-numerical switches and impulse re-

sponsive numerical switches, a line relay indi-

vidual to said first line, a loop circuit including

said first line and the winding of said line relay, 40

said loop circuit being completed in response to

the initiation of a call at said substation, means

responsive to operation of said line relay for ex-

tending said loop circuit through one of said

non-numerical switches to one of said numerical 45

switches, whereby a connection may be routed

through said switches to said second line, a

second relay, an operating circuit for said sec-

ond relay, said operating circuit paralleling said

loop circuit as extended to said one of said non-

numerical switches, means comprising a uni- 50

directional conductive device for preventing said

second relay from operating when said operating

circuit is initially completed, means controllable

over said second line for causing current to 55

traverse said operating circuit in the proper di-

rection to cause operation of said second relay,

means responsive to operation of said second

relay for opening said loop circuit and for com-

pleting an auxiliary loop circuit extending 60

75 second loop circuit is completed, means respon-

through certain of said switches by way of which said connection is routed, and a relay controllable from said substation to open said auxiliary loop circuit and to recomplete the loop circuit 5 extending through said train of switches, said relay being released in response to the release of said connection.

7. In a telephone system, a pair of lines, means for establishing a connection between said lines, 10 said connection comprising a first loop circuit including the calling one of said lines and a second loop circuit including the called one of said lines, a relay, an operating circuit for said relay, said operating circuit paralleling a portion 15 of said first loop circuit, means comprising a unidirectional conductive device included in said operating circuit for preventing said relay from

operating in response to completion of said first loop circuit, means operative to cause current to traverse said operating circuit in the proper direction to cause operation of said relay when said second loop circuit is completed, means responsive to operation of said relay for opening said first loop circuit, means including a line switching relay individual to said calling line and controllable thereover for recompleting said first loop circuit, said line switching relay being 10 released in response to the release of said connection, and a numerical switch having access to said calling line, said line switching relay also being operative in response to seizure of said calling line by said numerical switch. 15

HARRY G. EVERSON.
